[57] **CLAIM**

The ornamental design for a combined film container and reversible cap, as shown and described.

DESCRIPTION

FIG. 1 is a front perspective view of a combined film container and reversible cap showing my new design in an exploded condition;

FIG. 2 is an exploded perspective view of the combined film container and reversible cap with the cap shown in the inverted position;

FIG. 3 is a top plan view of FIG. 1;

FIG. 4 is a top plan view of FIG. 2;

FIG. 5 is a rear perspective view of the combined film container and reversible cap shown in a closed position;

FIG. 6 is a side elevation of FIG. 5, the opposite side is

the same;

FIG. 7 is a side elevation of the combined film container and reversible cap shown with the cap in the inverted and closed position;

FIG. 8 is a top plan view of the film container shown without the cap for clarity of illustration; and,

FIG. 9 is a bottom plan view of FIG. 8.
